CIGARETTE LIGHTER

Shirley McLarty, Dallas, Tex., assignor, by mesne assignments, to American Lighter Corporation, Fort Worth, Tex., a corporation of Texas

Filed May 18, 1964, Ser. No. 80,033

Term of patent 14 years

(Cl. D48—27)

FIG. 3

FIG. 2

FIG. 1

FIGURE 1 is a side elevational view of a cigarette lighter incorporating the design of this invention;

FIGURE 2 is a front elevational view of the lighter of FIGURE 1; and

FIGURE 3 is a top plan view of the lighter of FIGURES 1 and 2.

The bottom of the lighter shown in FIGURES 1-3, is plain, and the sides not shown are similar to the sides shown, except the sides not shown do not include any projecting lever or button.

I claim:

The ornamental design for a cigarette lighter, as shown and described.
